(57) **CLAIM**

The ornamental design for an earring, substantially as shown and described.

DESCRIPTION

FIG. 1 is a front elevational view of an earring showing my new design;

FIG. 2 is a left side view thereof;

FIG. 3 is a rear view thereof;

FIG. 4 is a right side view thereof; and,

FIG. 5 is a perspective view thereof.

The broken lines are for illustrative purposes only and form no part of the claimed design.
